UNITED STATES PATENT OFFICE.

CAROLINE A. HINSCH AND WILLIAM G. PRICE, OF SIOUX CITY, IOWA.

SKATE.

SPECIFICATION forming part of Letters Patent No. 544,172, dated August 6, 1895.

Application filed December 28, 1894. Serial No. 533,189. (No model.)

To all whom it may concern:

Be it known that we, CAROLINE A. HINSCH and WILLIAM G. PRICE, citizens of the United States, residing at Sioux City, in the county of Woodbury and State of Iowa, have invented certain new and useful Improvements in Skates; and we do hereby declare the following to be a full, clear, and exact description of the invention, such as will enable others skilled in the art to which it appertains to make and use the same.

Our invention relates to improvements in skates; and it consists of an improved construction whereby they have an improved spring action under the feet of the skater, as hereinafter specifically described and claimed.

In the accompanying drawings, forming part of this specification, Figure 1 represents a side elevation of a skate embodying our invention and having a single spring action. Fig. 2 represents a side elevation of said skate applied to a skater's foot, the split spring-runner being shown in its compressed position. Fig. 3 represents a side elevation of a modified form of our invention in which the skate has a double spring action, and Fig. 4 represents a rear elevation of the form of skate shown in Figs. 1 and 2.

A in the drawings represents the sole-plate; B, the clamping devices, and D the runner.

The sole-plate A is constructed in the ordinary manner and is provided with any suitable clamping devices by which it may be secured to the skater's foot.

The runner D has its lower edge either flat or concave, as desired, and is made of spring metal. This runner is split longitudinally, so as to form an upper sole-plate-attaching portion d and a lower spring-runner d', the action of the spring metal being to keep said portions normally separated, as shown in Fig. 1. The width of the space between the portions d d' is greatest at the rear and gradually decreases toward the front where said split in the runner ends, leaving the forward end or toe of the runner solid.

The rear end of the portion d' is turned upward at right angles, as at d², and is provided with a vertical slot d³, closed at the top. The rear end d⁴ of the portion d has its

lower edge beveled to form a knife-edge d⁵, and said end is adapted to be guided vertically by sliding in the slot d³. The portion d' at the lower end of the slot d³ is beveled downward toward the rear, as at d⁶, and thus any snow or ice accumulating in the slot d³ will be forced or cut out of the same as the portions d d' approach each other by the combined action of the knife-edge d⁵ of the portion d and the bevel d⁶ of the portion d'.

In Fig. 3 we have shown a double spring-runner. This is constructed in substantially the same manner as that shown in Fig. 1, with the exception that the forward end or toe portion of the runner is provided with a projecting nose d⁷, and the portion d' is made higher and is split from the front toward the rear to form an intermediate spring portion d⁸. The forward end d⁹ as well as the rear end d¹⁰ of said runner is turned upward. The end d⁹ is provided with a vertical slot similar to slot d³, said slot having a beveled bottom similar to d⁶. The end d⁷ is also provided with a knife-edge similar to edge d⁵, and said end works in the slot d⁹ in exactly the same manner that end d⁴ works in the slot d³.

The compression and expansion of the spring-runners as the skater moves along takes the place of the knee movement necessary in the ordinary construction of skate, so that nearly all the movement that the skater need make to move forward is to sway the body from side to side. As the body sways or leans to the right the pressure is on the spring of the right skate, which compresses it, as shown in Fig. 2. The left foot in the meantime is allowed to drop behind, and as the pressure is removed from the spring on the left skate it expands and pushes the skater forward, and so on vice versa. While this spring action makes a forward movement in straight lines very easy, it also is advantageous for fancy skating in curved lines.

What we claim as our invention, and desire to secure by Letters Patent, is—

1. In a skate the combination with a suitable sole plate, of a spring runner consisting of a single piece of metal split longitudinally along a portion of its length and having said split portions bent apart so as to be normally separated; one of said portions being

attached to the sole plate and the other being free and capable of vertical spring movement, substantially as described.

2. In a skate the combination with a suitable sole plate and clamping devices, of a spring runner consisting of a single piece of metal split along a portion of its length and having said split portions bent apart; one of said portions being attached to the sole plate and the other being free so as to be capable of vertical spring action, and devices for guiding the vertical movements of said runner, substantially as described.

3. In a skate the combination with a suitable sole plate and clamping devices of a spring runner consisting of a single piece of metal split along a portion of its length and having said split portions bent apart so as to be capable of vertical spring action, one of said portions being provided with a slotted extension, and the other with a projecting nose adapted to slide and be guided in said slotted extension, substantially as described.

4. In a skate the combination with a suitable sole plate and clamping devices of a spring runner consisting of a single piece of metal split along a portion of its length, and

having said split portions bent apart so as to be capable of vertical spring action, the lower portion being provided with an upwardly extending slotted portion, the lower wall of the slot being beveled, and the upper portion being provided with a projecting nose having a knife edge and adapted to slide and be guided in said upwardly extending portion, substantially as described.

5. In a skate the combination with a suitable sole plate and clamping device of a spring runner consisting of a single piece of metal split along a portion of its length from the front toward the rear, and from the rear toward the front so that said runner is capable of vertical spring movement at its forward and rear ends, and devices for guiding the split portions of the runner in their vertical movements, substantially as described.

In testimony whereof we have affixed our signatures in presence of two witnesses.

CAROLINE A. HINSCII.
WILLIAM G. PRICE.
